UNITED STATES PATENT OFFICE.

CHARLES P. MOSHER, OF SYRACUSE, NEW YORK, ASSIGNOR TO THE MONARCH TYPEWRITER COMPANY, OF SYRACUSE, NEW YORK, A CORPORATION OF NEW YORK.

TYPE-WRITING MACHINE.

No. 923,438.

Specification of Letters Patent.

Patented June 1, 1909.

Application filed July 6, 1904. Serial No. 215,526.

To all whom it may concern:

Be it known that I, CHARLES P. MOSHER, citizen of the United States, and resident of Syracuse, in the county of Onondaga and State of New York, have invented certain new and useful Improvements in Type-Writing Machines, of which the following is a specification.

My invention relates to typewriting machines.

One of the objects of my invention is to provide a wide carriage typewriting machine.

Another object of my invention is to provide a construction whereby a typewriting machine may be equipped readily with interchangeable carriages of different widths or platens of different lengths.

In the machine shown and described in the present case a plurality of platen frames are provided and one of these frames may be readily detached from the carriage truck, and another platen frame substituted for it. The different platens may differ in composition, one platen being of hard material and another of comparatively soft material. The platens and platen frames may also differ in length, so that the same machine may be used as either a wide carriage machine or a narrow carriage machine. I have provided novel means whereby either a short or a long platen frame may be detachably mounted on the truck. I have also devised novel supports for the carriage rails so as to accommodate a long tabulator bar for use in connection with the wide carriage. I have also provided a carriage release mechanism, part of which is on the truck and part of which is on the detachable platen frames.

The typewriter shown in this case is a front-strike machine and is provided with a ribbon vibrator. I have mounted this ribbon vibrator in such manner that it can be moved out of the way when a platen frame is removed from the machine and restored to normal position when a platen frame is mounted on the machine. I have also provided means whereby this movement of the ribbon vibrator is effected automatically, and the vibrator is held in either of its positions.

My invention has other objects which will be appear hereinafter.

My invention consists in the various features of construction and combinations and

arrangements of parts, all as will be herein-after more fully described and particularly pointed out in the claims.

One embodiment of my invention is illustrated in detail in the accompanying drawings in which,

Figure 1 is an end elevation of a typewriting machine having two interchangeable platen frames, the long frame being shown in position on the machine; Fig. 2 is a front to rear sectional view of the same; Fig. 3 is a view similar to Fig. 1 of a portion of the mechanism, illustrating the manner in which the platen frame is removed from the machine; Fig. 4 is a plan view showing a portion of the ribbon mechanism and certain connections between the same and the detachable platen frame; Fig. 5 is a back view, partly in section, of a portion of the mechanism; Fig. 6 is an end elevation, partly in section, showing the short platen frame in position on the machine; Fig. 7 is a similar view of the same parts but in a position they occupy when the platen is being removed from or placed on the machine; Fig. 8 is a top plan view of part of the machine showing the long platen frame in position on the machine; Fig. 9 is a similar view showing the short platen frame in position on the machine; Fig. 10 is a front elevation showing the long platen in position; Fig. 11 is a rear elevation of the machine, the long platen being in position thereon; and Fig. 12 is a sectional view of one of the platen frames.

I have shown my invention applied to the Monarch front-strike typewriter. The main frame of this machine comprises a base portion 1, from which rise posts 2, which support a top plate 3. Keys 4 are mounted on the ends of key levers which are pivoted near the back of the machine and which operate upwardly and rearwardly striking type bars which carry types which strike against the front face of the platen 5. This mechanism is well known, and it has not been thought necessary to show it in the present case. A carriage truck 6 has raceways formed in its upper and lower edges, and said truck is supported by antifriction balls or rollers 7 which run in said raceways and in co-operating raceways formed in a lower fixed rail 8 and an upper fixed rail 9.

As shown, for example, in Fig. 11, the length of these rails exceeds the width of the

main frame and said rails are accordingly supported at points intermediate their ends by two brackets 10 which are secured to the top plate of the machine by screws 11 (Fig. 5 1). In the present instance these brackets are shown formed with a U-shaped cross-section for the sake of lightness and stiffness. The lower rail 8 is secured to the brackets 10 by screws 12 (Fig. 11) passing through 10 said brackets and threaded into said rails. The upper rail 9 has two brackets 13 secured thereon by screws 14 (Fig. 11) and 15 (Fig. 8). These brackets are rigidly secured to the brackets 10 by screws 16 (Fig. 11) which 15 pass through said brackets 10 and are threaded into said brackets 13. Each pair of brackets 10 and 13 constitutes in effect a single bracket rising from the top plate 3 and supporting the upper rail 9. This 20 compound bracket has the arched form shown in the drawings for a purpose which will appear hereinafter. The rails 8 and 9 are connected together near each end by a bracket or frame piece 17 which projects back from 25 the rear surfaces of said rails, to which it is secured by screws 18 passing through ears 19 of said frame piece and threaded into said rails. The carriage truck 6 may be drawn across the machine by the usual spring drum 30 and connections or by any suitable means.

As shown, for example, in Fig. 3, two brackets 20 project from the truck 6 toward the front of the machine, one of said brackets being near each end of said truck. A 35 feed rack 21, which lies back of the truck, is rigidly mounted at its ends on arms 22, which are pivoted on headed and shouldered screws 23, which are threaded into said brackets 20. The arms 22 normally rest on 40 stop pins 24, against which they are pressed by the weight of the parts and also by the tension of a spring or springs 25 (Fig. 11). I have shown two such springs, each of which passes over a screw 26 threaded into 45 the truck 6 and under a pin 27 on said truck and which presses at its free end on the rack bar. The rack bar 21 is geared to a pinion 28 fixed on a shaft 29, which is journaled in the framework and which has mounted 50 thereon an escapement wheel 30, which is controlled by escapement dogs (not shown).

The truck 6 has projecting from the front face thereof two pairs of brackets 31 and 32 by which the detachable platen frames are 55 supported, the brackets 31 being designed for the long platen frame and the brackets 32 being a less distance apart than the brackets 31 and being designed for the short platen frame. The positions of these brackets 60 lengthwise of the truck are best shown in Fig. 8. Each of the brackets 31 and 32 has in its upper face a depression 33 (Fig. 8) to receive a rod which is rigidly mounted on the detachable platen frame, so that the brackets 65 in effect are hooks on which the platen

frame is hung. I have shown two platen frames in the present case, one being of the usual or standard length and the other a long platen frame. These frames are nearly alike in construction and each comprises two end pieces 34 and 35 connected together by an upper frame rod 36 and a lower frame rod 37. The upper frame rod 36 is connected at its ends to brackets 38 (Fig. 1) rising from the end pieces 34-35. These brackets are shown 70 in Figs. 8 and 9 but the rods are omitted from those figures. The lower frame rod extends through brackets 39 (Fig. 1), in which it is secured by set screws 40. The end pieces 34-35 have the angular form best 80 shown in Figs. 8 and 9, by reference to which it will be seen that each of said end pieces comprises an arm which lies back of the platen and substantially parallel with the axis of the platen, and another arm at right angles 85 to the first one and extending toward the front of the machine and having the platen shaft journaled therein. As will be best understood by reference to Fig. 9, the back 90 arm of each of the end pieces which lies parallel with the platen has an upwardly opening notch or slot formed therein to receive the brackets 31 or 32, the walls 41 of said notch or slot being shown in said Fig. 9. Two lugs or ears 42 also rise from said arm, 95 leaving between them another upwardly open notch or slot 43. A rod 44, seated in a longitudinal opening in said arm, extends across the two notches referred to and it is this rod that rests in the notch or hook 33 of 100 the brackets 31, 32 and supports the platen frame. Within the notches 43 are pivoted the arms of a paper guide plate which will be described hereinafter. The back arm of each of the end pieces 34-35 has projecting 105 from its inner end toward the front of the machine a bracket 45 (Fig. 9) having a notch 46 in one surface thereof, and a headed screw threaded into an opening 47 in said bracket (Fig. 2) supports an arm of a paper table of 110 the usual construction. It will be perceived, therefore, that the paper feeding devices are mounted on the end pieces of the platen frames, thus leaving the frame rod 37 free throughout substantially its entire length. 115 The purpose of this arrangement will presently appear. As will be understood by reference to Fig. 2, the truck 6, which is preferably made of an integral piece, comprises an upper and lower rail or track which extends 120 the entire length of said truck, and these rails are connected together by a sort of web which, as shown in the present instance, is not continuous, but consists of a series of cross pieces 48 (Fig. 11), this web portion being of less thickness than the thickness of the rails. Each of the end pieces 34-35 has a 125 backwardly extending projection 49 (Figs. 2 and 9), which, when the platen frame is in position on the machine, enters the space be- 130

tween the two rails of the truck and interlocks with these parts of the truck in such a manner that the rods 44 cannot be lifted out of the notches 33 without first imparting to 5 the platen frame a preliminary motion which consists in tilting it to the position shown in Figs. 3 and 7, this tilting of the platen frame disengaging the interlocking parts of the said frame and truck. It will be perceived that 10 the platen frame is of an overhanging construction and that when it is in position on the machine, its own weight tending to turn it about the rods 44 as a pivot, presses the flat rear faces of the end pieces against the 15 front of the truck and holds the interlocking parts of the platen frame and truck in engagement.

The pins or rods 44 resting in the notches or depressions 33 constitute one connection 20 between the truck and the platen frame and the projections 49 and the coöperating depressions in the truck constitute another connection between these parts, and it will be perceived that these two connections are 25 so related that when the parts are in normal position the connection 49 prevents disengagement of the connection 33, 44, and that these connections are also so related that the connection 49 must be disengaged by a preliminary movement of said frame before the other connection 33, 44 can be disengaged, said preliminary movement consisting of a swinging movement of the platen frame about the connection 33, 44 as a pivot. 30

35 In order to prevent accidental displacement of the platen frame, I have provided latches which are adapted to prevent the preliminary motion of said frame, above referred to. These latches are arranged somewhat differently on the long and the short platen frames.

As shown in Fig. 3, the end pieces of the long platen frame have formed in their surfaces depressions 50, which when the platen 45 frame is in working position, fit over the brackets 20 of the truck 6. A lever 51 is pivoted to the end piece on a headed and shouldered screw 52 and said lever is formed on its rear end with a hook 53 which snaps into 50 a notch 54 in the underside of said brackets 20. The lever 51 has a forwardly extending arm which is pressed downward by a spring 55 secured to the end piece. The platen frame may be provided with one of these 55 latch levers at one end thereof, but I prefer to use two such latches, one at each end. The levers 51 lie in such position that the platen frame may be very readily removed by grasping it in the manner shown in Fig. 3. 60 The operator takes hold of the finger wheel 56 of the platen and at the same time presses up on the lever 51 with one of his fingers, thus unhooking the latch. The platen frame may then be tilted to the position shown in 65 Fig. 3 to disengage the interlocking members

above referred to and may then be lifted off the machine. It will be perceived that the platen frame may thus be removed from the machine by practically a single motion of the hands.

The short platen frame does not reach to the brackets 20 and the latches for this frame are accordingly arranged differently from those of the long platen. As shown in Fig. 7 the end pieces of this platen frame have a depression 50 similar to the depression 50 of the long platen frame. Within this depression a latch lever 57 is pivoted on a shouldered and headed screw 58 which is threaded into the end piece. The lever 57 70 has a rearwardly extending arm, the end of which forms a hook 59 which is adapted to engage in a notch 60 formed in the upper surface of the lower rail of the truck. The arm 57 has a forwardly and downwardly extending arm to which is connected one end of a spring 61, the other end of which is secured to a pin 62 which projects from the end piece of the platen frame, the tension of this spring tending to hold the latch in its notch. 75 A lever 63 is pivoted to the end piece on a shouldered and headed screw 64, and a rearwardly extending arm of this lever engages the forwardly extending arm of the lever 57. The lever 63 has a forwardly extending arm 80 similar to the corresponding arm of the lever 51, which constitutes a finger piece by which the said lever is operated in the manner shown in Fig. 7. It will be perceived by reference to said figure that if the finger wheels 85 56 of the short carriage be grasped by the hand, one of the fingers may press upward on the lever 63 and that the hook 59 will be then lifted out of the notch 60, and this platen frame may be removed from the machine in the same manner as the long frame. 90

The long platen frame has on each end thereof a release lever 65, which is pivoted on a headed and shouldered screw 66. The motion of said lever about its pivot is limited by a pin 67 which projects from the end piece of the platen frame into a notch in the lever. Said lever has a rearwardly extending arm which, when the platen frame is in position on the machine, lies beneath a lug or ear 68 of the arm 22 of the rack bar 21. The construction is such that if the forward end of the lever be depressed, the rack bar will be lifted out of engagement with its pinion. The short platen frame does not reach to the 110 arms 22. This platen frame has a release lever 69 pivoted on a screw 70 and the motion of said lever is limited by a pin 71, the arrangement being similar to that on the other frame. The rearwardly extending arm of the lever 69 lies beneath a lever 72 (Figs. 6 and 7), which is pivoted on a screw 73, which is threaded into one of the web pieces 48 of the truck 6. Said lever extends longitudinally of the truck and at its free end lies 115 120 125 130

beneath one of the arms 22. As shown in Fig. 9, the lever 69 lies beneath the lever 72 between the pivot 73 and the arm 22, so that when the lever 69 is depressed the lever 72 will be lifted and will raise the arm 22 and rack bar 21.

The present machine is provided with a ribbon vibrator as usual, and I have provided means for moving the vibratory ribbon guide 10 out of the way when the platen frame is removed from the machine. The ribbon is wound on spools in the usual or any suitable manner and is conducted past the printing point by a guide plate 74, which is moved up 15 and down in grooves in a guide frame 75 by an arm 76 having an open ended slot which receives a pin 77 secured in a depending portion 78 of the guide plate 74. The arm 76 is vibrated by the keys in the usual manner. 20 The guide frame 75 is pivoted to ears 79 which are secured by screws 80 to brackets 81 which are secured by screws 82 to the underside of the top plate 3. The construction is such that the guide frame 75 may move 25 about its pivots to its normal position, shown in Fig. 1, or to its out of the way position shown, for example, in Fig. 3. This motion of the guide frame is controlled by a link 83 which is pivoted at its front end to the guide 30 frame on a pin 84, and which is pivoted at its rear end at 85 to a lever 86, which is pivoted at 87 to a bracket 88, which is secured by screws 89 to the top plate 3.

As shown in Fig. 4, the screws 89 pass 35 through elongated slots in the bracket 88, which arrangement permits of adjusting said bracket front and back of the machine in order to bring the guide frame to the correct position in front of the platen. A coiled 40 spring 90 connected at one end to the top plate 3 and at the other end to the link 83, tends to draw said link toward the front of the machine. The construction is such that when the lever 86 is in its normal position 45 shown in Fig. 1 the pivot point 85 of the link 83 is below the dead center, so that the spring 90 tends to hold the guide frame in its normal position, but when the lever 86 is moved to the position shown in Fig. 3 this pivot 50 point passes the dead center so that the spring tends to hold the guide frame in either of its two positions. The motion of the lever 86 under the impulse of the spring 90 is limited in one direction by the top plate 3 and in the 55 other direction by a lug 91 (Fig. 4) projecting from the bracket 86 into the path of said lever. The lever 86 has two arms 92 and 93, which, when either platen frame is in position on the machine, embrace the frame rod 37 60 of said platen frame, this rod sliding along in the fork formed by said arms as the carriage moves to and fro across the machine. This is one reason why the rod 37 is left free throughout its length. It will be perceived 65 that when the platen frame is in position on

the machine the rod 37 locks the lever 86 in the position shown in Fig. 1, so that the guide frame 75 is positively held in normal position when the machine is in use. When the platen frame is tilted, as shown in Fig. 3 70 or Fig. 7, to remove the same from the machine, the rod 37 automatically moves the lever 86 to its forward position before the platen frame is lifted from the machine and said lever is held in this position by the 75 spring 90. When the platen frame is placed in position on the machine the rod 37 thereof automatically restores the lever 86 and ribbon guide to normal position. It will thus be perceived that the movement of the ribbon guide into and out of its normal position as a platen frame is placed on or removed from the machine is entirely automatic. This movement of the ribbon guide may, of course, be effected by hand if preferred. 80

I have made certain changes in the tabulator mechanism in order to adapt it to this machine in which a long platen is used. A stop 94 (Fig. 11) is secured to the rear face of the truck 6 and co-operates with a stop or 90 stops 95 (Fig. 2) which is mounted on an oscillatory tabulator bar 96 in the usual manner. This bar has notches or slots cut in its surface a letter space distance apart, and the stops 95 may be set in any one of these 95 notches, being held therein by a spring 97 (Fig. 2) in a well known manner. The stop 95 is normally out of the path of the stop 94, but may be moved into the path of said stop by rocking the bar 96 toward the front 100 of the machine. The bar 96 is mounted at or near its ends on the brackets 17 in a manner best shown in Fig. 5, which is a rear view of this portion of the mechanism. At its right-hand end the rod 96 passes loosely 105 through an opening in one of the brackets 17 and at its left-hand end said bar is formed with a central longitudinal opening 98 which fits loosely over a rod or pin 99 which is enlarged at its outer end, forming an annular 110 shoulder 100 against which the end of the bar 96 normally stands. The enlarged portion of the rod 99 is threaded through the left-hand bracket 17 and is formed at its end with a milled head 101. The bar 96 may be 115 adjusted lengthwise by turning said milled head, thus adjusting the position of the pin 99, which is secured in adjusted position by tightening a lock nut 102. It is, of course, necessary that no stationary part of the 120 mechanism shall stand between the bar 96 and the truck, and it is for this reason that the brackets 10 have the arched form shown in the drawings, so that the bar 96 may lie between said brackets and said truck. The 125 bar 96 thus passes through a sort of opening in the framework and it may happen that it is desired to adjust one of the stops 95 to a position within this opening behind one of the brackets 10, as shown in Fig. 5. To facili- 130

tate this adjustment of the stops, the bar 96 is so mounted that it may be moved endwise so as to bring the portions thereof which normally lie beneath the brackets to accessible positions. The pin 99 is made of a length sufficient to permit of such motion. The opening 98 in the bar 96 is formed near the end of said bar with an annular groove or enlargement 103 into which extends the curved end of a spring 104 which lies in a longitudinal slot formed for the purpose in the pin 99. Said spring is secured in position by a screw 105 threaded into said pin and engaging said spring. The rocking motion of the bar 96 is controlled by an arm 106 (Fig. 1), the hub 107 of which (Fig. 5) is mounted on said rod just outside the right-hand bracket 17. In order to permit of the longitudinal motion of the tabulator bar above referred to, the hub 107 is loosely mounted on said bar and is connected thereto by a pin or screw 108 which is threaded into said hub and the inner end of which projects into a longitudinal slot 109 in the bar, so that the hub and bar are constrained to turn together. The longitudinal motion of the bar 96 toward the right is limited by the engagement of the screw 108 with the end of the slot 109. In order to prevent the hub 107 from moving away from the bracket 17, said hub is formed with a peripheral groove 110 into which projects the head of a screw 111 which is threaded into said bracket.

The rocking motion of the bar 96 is controlled by a tabulator key 112 (Fig. 2) which is mounted on the end of a key lever 113 which is pivoted at its rear end at 114. A pin 115 projects from one side of said key lever into a slot 116 in an ear 117 of a lever 118, the front end of which is pivoted at 119 to a bracket depending from a portion of the main frame. The lever 118 is connected at its rear end to the lower end of a link 120 which passes loosely through an opening in the back shelf 121 of the main frame and extends above the top plate 3. The link 120 has a collar 122 fixed thereon by a set screw 123 (Fig. 2), and a coiled spring 124, compressed between said collar and the shelf 121, holds said link in its normal position. Projecting from the collar 122 toward the front of the machine is an arm 125 which stands above a lever 126 so that when the tabulator key is depressed said arm depresses said lever, which operates a release device which raises the feed rack out of engagement with its pinion. This release device is old and well known and is not shown herein. As best shown in Figs. 2 and 11, the link 120 is pivoted at its upper end to the free end of an arm 127 which is fixed to and projects toward the back of the machine from a rock shaft 128, which is journaled at one end in an opening 129 (Fig. 7) in one of the brackets 10, and at the other in one of the brackets 17.

An arm 130 (Fig. 1) is fixed on the outside end of the shaft 128, and said arm is connected by a link 131 with the arm 106 which is mounted on the tabulator bar 96. The construction is such that if the tabulator key be depressed, the link 120 will be drawn downward, the shaft 128 will be rocked toward the back of the machine and the tabulator bar 96 will be rocked toward the front of the machine, bringing the tabulator stop into the path of the carriage stop, the lever 126 releasing the carriage from the escapement mechanism. It will be perceived that the rock shaft 128 has been interposed in the connections between the tabulator key and the tabulator bar in order to carry such connections out to the end of the long tabulator bar used in this machine.

The margin stops are mounted on an oscillatory bar 132 which is journaled in brackets 133 rising from the top stationary rail 9. This bar does not differ materially from the bar ordinarily used in the Monarch typewriter, except in that it is longer and the connections between said bar and the carriage release key have been extended out to its end in a manner somewhat similar to those of the tabulator key and bar. The margin stop bar has projecting from one end thereof toward the back of the machine, an arm 134 (Fig. 1), having a pin 135 which works in a slot 136 in the upper end of a link 137, the lower end of which is pivoted at 138 (Fig. 2) to an arm 139 (Fig. 11) of a yoke frame 140, which is journaled on the rock shaft 128. The yoke 100 frame 140 extends beyond the arm 127 of said rock shaft and at its inner end has a rearwardly projecting arm 141 (Fig. 2) which is connected by a link 142 to the rearwardly extending arm of a bell crank lever 143, which is pivoted on a shouldered and headed screw 144, which is threaded into a bracket 145 secured to one of the rear posts of the main frame by screws 146 threaded into ears 147 of said post. Said rearwardly extending arm 110 of the bell crank 143 is normally drawn against a stop pin 148 projecting from the bracket 145 by a coiled spring 149 which is connected at one end to said stop pin and at the other end to a bracket 150 depending from said bell crank. Said bell crank has an upwardly extending arm to which is pivoted a push rod or bar 151, which extends to the front of the machine and has a margin release key 152 mounted on its front end. The forward end of the bar 151 is guided by an opening in a frame piece 153 through which said bar loosely passes. The construction is such that if the release key 152 be pushed toward the back of the machine, the bell crank 143 will be rocked, the link 142 will draw the arm 141 downward, rocking the yoke frame 140 toward the back of the machine, thus pulling down the link 137 and rocking the stop bar 132 toward the back of the machine. This

motion of the stop bar permits the margin stop to pass the coöperating stop on the framework in a manner which is old and well known. Said stop bar is provided with the usual returning spring 154 and finger buttons 155.

The paper feeding devices are best shown in Fig. 12. As shown in Fig. 8, two arms 156 are pivoted on the rods 44 between the ears 42. As shown in Fig. 12, these arms extend down behind the platen and are connected together by a rod 157 on which are journaled feed rollers 158 which are pressed against the platen by springs 159 secured to the arms 156 and pressing against adjusting screws 160 threaded through the longitudinally extending arms of the end pieces of the platen frame. A rod 161 is mounted in each of the end pieces of the platen frame and arms 162 are pivoted on said rods and extend forward under the platen and are connected together by a rod 163 on which are journaled pressure rollers 164. The arms 162 are pressed toward the platen by springs 165 secured to the end pieces of the platen frame and pressing against said arms. The feed rollers 158 lie in openings in an apron 166; brackets 167 of which are pivoted on a rock shaft 168. The apron is pressed against the platen by springs 169 secured to the arms 162 and engaging said apron. The rock shaft 168 has short arms 170 projecting therefrom in position to engage lugs 171 on the arms 156. The shaft 168 may be rocked by a lever which is not shown herein and the arms 170 will depress the arms 156, moving the feed rollers 158 out of engagement with the platen, and the rod 157 engaging the arms 162 will depress said arms and move the rollers 164 out of engagement with the platen, and the springs 169 moving downward with the arms 162 will permit the apron to drop away from the platen.

A platen plate 172, the front surface of which is graduated to constitute a platen scale and a carriage scale, is supported by spring arms 173 which are secured by screws 174 to the underside of the longitudinally extending arms of the end pieces of the platen frame. It will thus be perceived that the paper feeding devices are mounted on the L-shaped end pieces of the platen frame.

Various changes in the details of construction and arrangement may be made without departing from the gist of my several improvements.

The carriage stop mechanism shown is not claimed herein but is claimed in my Patent No. 843,545, granted February 5th, 1907, on an application which was a division of the present case.

What I claim as new and desire to secure by Letters Patent, is:—

1. In a typewriting machine, the combination of a truck; means for securing a long

platen to said truck; and separate means for securing a short platen to said truck.

2. In a typewriting machine, a carriage truck having different means for supporting platen frames of different lengths. 70

3. In a typewriting machine, the combination of a carriage truck, a platen frame mounted on said truck and having two angled end pieces connected together by frame rods, one arm of each of said angled end pieces extending substantially lengthwise of the platen frame and being connected with said truck; and paper feeding devices mounted on said arms. 75

4. In a typewriting machine, the combination of a carriage truck, a platen frame mounted on said truck and having two angled end pieces connected together by frame rods, one arm of each of said angled end pieces extending substantially lengthwise of the platen frame and being connected with said truck, and the other arm being substantially at right angles thereto; a platen mounted on the latter arms; and paper feeding devices mounted on said longitudinally extending arms. 80

5. In a typewriting machine, the combination with a carriage truck, of a platen frame having end pieces connected together by frame rods, each of said end pieces having two arms at an angle to each other; a platen journaled in one arm of each end piece, the other arm of each end piece having means whereby said platen frame is detachably supported on said truck, and said detachable supporting means constituting the sole support of said platen frame. 95

6. In a typewriting machine, the combination with a carriage truck, of a platen frame having end pieces connected together by frame rods, each of said end pieces having two arms at an angle to each other; a platen journaled in one arm of each end piece, the other arm of each end piece having means whereby said platen frame is detachably supported on said truck; and paper feeding devices mounted on the last mentioned arms. 105

7. In a typewriting machine, the combination of a carriage truck and a platen frame detachably mounted on said truck, said truck and frame having coöperating devices whereby said frame is supported by said truck, and also interlocking parts which prevent said frame from being lifted off of said truck but which are adapted to be disengaged by a preliminary movement of said frame. 115

8. In a typewriting machine, the combination of a carriage truck; a platen frame detachably mounted on said truck, said frame and truck having coöperating devices by which said frame is supported on said truck and also having interlocking parts which are disengaged by a preliminary swinging motion of said frame. 125

9. In a typewriting machine, the combination of a carriage truck, means on said truck for supporting a platen frame; and a platen frame detachably mounted on said truck and having a latch engaging a portion of said truck to prevent motion of said platen frame relative to said supporting means.
10. In a typewriting machine, the combination of a carriage truck; a platen frame detachably mounted on said truck, said frame and truck having coöperating devices whereby said frame is supported by said truck, and also interlocking parts which prevent said frame from being lifted off of said truck but which are adapted to be disengaged by a preliminary movement of said frame; and a latch for preventing such preliminary movement.
11. In a typewriting machine, the combination of a carriage truck, a platen frame, said frame and truck having coöperating devices whereby said frame is supported by said truck, and also interlocking parts which prevent said frame from being lifted off of said truck but which are adapted to be disengaged by a preliminary movement of said frame; and a ribbon guide which is moved out of the way by such preliminary movement.
12. In a typewriting machine, the combination of a carriage truck; a platen frame detachably mounted on said truck, said frame and truck having coöperating devices by which said frame is supported on said truck, and about which said frame may have a swinging motion; and a latch for normally preventing said swinging motion.
13. In a typewriting machine, the combination of a carriage truck; a platen frame detachably mounted on said truck, said frame and truck having coöperating devices by which said frame is supported on said truck and also having interlocking parts which are disengaged by a preliminary swinging motion of said frame; and a latch for normally preventing such preliminary swinging motion.
14. In a typewriting machine, the combination of a carriage truck; a platen frame detachably mounted on said truck; a platen mounted in said platen frame and having finger wheels; a finger piece mounted on said frame near one of said finger wheels so that said finger piece and said finger wheel may be grasped at the same time by a hand of the operator; and a latch for said frame controlled by said finger piece.
15. In a typewriting machine, the combination of a carriage truck; a feed rack having arms pivoted to said truck; a lever pivoted to said truck and extending longitudinally of said truck and adapted to raise one of said arms; a platen frame mounted on said truck and differing in length from said feed
- rack; and a release key on said platen frame, 65 said release key being adapted to operate said lever.
16. In a typewriting machine, the combination of a carriage truck adapted to support platen frames of varying lengths, a feed rack mounted on said truck, a pinion meshing with said feed rack, a platen frame shorter than said carriage truck and detachably mounted thereon, a release key on said short platen frame, and a lever pivoted on 70 said carriage truck and operative by said release key to raise said feed rack out of engagement with said pinion.
17. In a typewriting machine, the combination of a carriage truck adapted to support platen frames of varying lengths, a feed rack mounted on said truck, a pinion meshing with said feed rack, a platen frame shorter than said carriage truck and detachably mounted thereon, a release key on 75 said short platen frame, and a lever pivoted on said carriage truck and operative by said release key to raise said feed rack out of engagement with said pinion, said lever being inoperative when the short platen frame is 80 replaced by a long platen frame and the release key of the latter is actuated.
18. In a front-strike typewriting machine, the combination of a platen removably mounted on the machine; a ribbon guide 95 which normally stands in front of said platen; and means for automatically moving said ribbon guide out of the way when said platen is removed from the machine.
19. In a typewriting machine, the combination of a platen removably mounted on the machine; a ribbon guide; and means for automatically moving said ribbon guide out of normal position when the platen is removed from the machine and restoring it to 100 normal position when the platen is replaced.
20. In a typewriting machine, the combination of a removable platen frame; a ribbon guide; and means for holding said ribbon 105 guide in normal position when the platen frame is in place on the machine, and moving it out of normal position when the platen frame is removed from the machine.
21. In a front-strike typewriting machine, the combination of a removable platen 115 frame; a ribbon guide pivotally mounted in front of the platen, so that it may be turned out of the way when the platen frame is removed; and means whereby said platen frame holds said ribbon guide in normal position when the platen frame is in place on the machine.
22. In a front-strike typewriting machine, the combination of a removable platen; a ribbon vibrator, a guide on which said vibrator is slidably mounted and which stands 120 in front of the platen, but which is capable of being moved out of the way when the

platen is removed from the machine; and spring means for holding said vibrator guide in either of its two positions.

23. In a typewriting machine, the combination of a removable platen frame; a ribbon guide; and means whereby said platen frame holds said ribbon guide in its normal position when said platen frame is in place on the machine, and moves said ribbon guide out of such normal position when said platen frame is removed from the machine.

24. In a front-strike typewriting machine, the combination of a removable platen frame including a rod which extends longitudinally 15 of said platen frame; a platen mounted in said platen frame; a ribbon guide pivotally mounted in front of said platen; and a lever pivoted to the main frame and controlled by said rod and controlling said pivotally 20 mounted ribbon guide, whereby said ribbon guide is held in normal position by said rod when the platen frame is in place on the machine, and is moved out of the way when said platen frame is removed from the 25 machine.

25. In a front-strike typewriting machine, the combination of a removable platen frame; a platen mounted in said frame; a vibratory ribbon guide; a pivotally mounted 30 member which guides said ribbon guide; and means for locking said member in normal position when the platen frame is in place on the machine, and for moving said member out of the way when said platen frame is re- 35 moved from the machine.

26. In a typewriting machine, the combination with the platen, of a ribbon vibrator, a guide on which said vibrator is slidably mounted and which guide is pivotally 40 mounted so as to be movable into and out of normal position; and spring means for holding said vibrator guide in either of its positions.

27. In a typewriting machine, the combination with the platen, of a ribbon guide which is pivotally mounted so as to be movable into or out of printing position; a lever for moving said ribbon guide; and a spring which passes from one side of a dead center 50 to the other when said lever is moved, whereby said spring holds said ribbon guide in either of its positions.

28. In a typewriting machine, the combination of a carriage truck; a platen frame 55 detachably mounted on said truck; a feed rack mounted on said truck, and engaging a pinion which is mounted on the stationary framework; a lever mounted on said truck and extending longitudinally thereof and 60 adapted to move said rack out of engagement with said pinion; and a release lever

mounted on said detachable platen frame and adapted to operate said lever.

29. In a typewriting machine, the combination of a carriage truck adapted to support 65 platen frames of different lengths, a feed rack mounted on arms pivoted to said carriage truck, a pinion mounted on a fixed part and normally meshing with said feed rack, a lever mounted on said truck and extending 70 longitudinally thereof, said lever being operative on one of the arms of said feed rack, a platen frame shorter than said carriage truck and detachably mounted thereon, and a release device mounted on said platen 75 frame and operative on said lever.

30. In a front-strike typewriting machine, the combination of a platen, a pivotally mounted ribbon vibrator guide upstanding in front of said platen and adapted to be 80 swung down and away from said platen, and a ribbon vibrator arranged to reciprocate in said guide.

31. In a front-strike typewriting machine, the combination of a platen, a pivotally 85 mounted upstanding ribbon vibrator guide arranged in front of said platen and adapted to be swung away from and, toward said platen, means for holding said guide in normal working position, and a ribbon vibrator 90 arranged to be reciprocated in said vibrator guide.

32. In a typewriting machine, the combination of a carriage truck, a frame detachably mounted on said truck, and a platen 95 carried by said frame, said truck and frame having two connections so related that when the parts are in normal position one of said connections prevents disengagement of the other, and also so related that one of said 10 connections must be disengaged by a preliminary movement of said frame before the other can be disengaged.

33. In a typewriting machine, the combination of a carriage truck, a frame detachably mounted on said truck, and a platen carried by said frame, said truck and frame having two connections so related that when the parts are in normal position one of said 11 connections prevents disengagement of the other, and also so related that one of said connections must be disengaged by a preliminary swinging movement of said frame about the other connection before said other connection can be disengaged. 11

Signed at Syracuse, in the county of Onondaga and State of New York, this 2nd day of July A. D. 1904.

CHARLES P. MOSHER.
